UNITED STATES PATENT OFFICE.

MARTON FRIDAY, OF BLUFFS, ILLINOIS.

WIRE-SPlicer.

972,844.

Specification of Letters Patent. Patented Oct. 18, 1910.

Application filed December 7, 1909. Serial No. 531,850.

To all whom it may concern:

Be it known that I, MARTON FRIDAY, citizen of the United States, residing at Bluffs, in the county of Scott and State of Illinois, have invented certain new and useful Improvements in Wire-Splievers, of which the following is a specification:

This invention relates broadly to wire working tools and refers particularly to an 10 implement for twisting the adjoining ends of wires in the erection of fences and the like.

This invention has for an object the provision of an implement of this character 15 which is so constructed that the wire may be held, twisted and cut by various operations of the implement, so as to form in one complete tool the essential elements for working with wire.

20 The invention has for a further object the provision of a tool of this character which may be operated by hand, and which will produce a neat joining of the wire by twisting the ends of the wire about one another and thereby forming a rigid connection.

25 The invention has for a further object the provision of a mechanism of this character which is provided with a hand-lever and a 30 ratchet mechanism whereby the wire may be twisted by the correct application of the hand-lever thereto for turning the same, and wherein the lever need only be reciprocated through a small arc to effect the operation 35 of the implement and thus produce a device which is operable in confined places.

For a full understanding of the invention reference is to be had to the following description and accompanying drawing, in 40 which:—

Figure 1 is a perspective view of the complete implement. Fig. 2 is a longitudinal section through the outer end of the same. Fig. 3 is a transverse section through the 45 outer extremity of the implement. Fig. 4 is a view of the same disclosing the ends of a wire in position to be twisted. Fig. 5 is an end view of the same, and Figs. 6, 7 and 50 8 disclose views of the ends of the wire in different stages during the twisting of the same.

Corresponding and like parts are referred to in the following description and indicated in all the views of the accompanying drawing by the same reference characters.

Referring to the drawing the numerals 16

and 11 designate a pair of handles which are provided at their outer ends with plates 12 and 13 having disposed centrally therethrough a pivot pin 14 for hingedly supporting the handles 10 and 11. The plates 12 and 13 are of circular formation and are provided at their opposite sides with transversely disposed slots 15 which are diagonally disposed and terminated in cutting 65 blades in the opposite faces of the plates 12 and 13 to form a means for cutting wire.

Disposed between the handles 10 and 11 are jaws 16 and 17 which are formed of different blocks of material and which are 70 welded or otherwise secured against the inner opposite faces of the handles 10 and 11.

The plate 13 carries at its forward edge a head 18 which is preferably integrally formed with the plate 13 and is offset at one 75 side of the plate 13 to dispose the side of the head 18 in forked relation with the outer face of the plate 12. The head 18 is provided at its lower edge with a pair of fingers 19 which are curved circularly and support 80 between the same a socket member 20. The socket 20 comprises an elongated sleeve which is transversely positioned across the outer end of the head 18 and is provided at one side with a longitudinal slot 21. Centrally about the socket 20 a ratchet 22 is 85 positioned, which is of such a width that the edges of the same engage against the inner faces of the fingers 19 to form a retaining means for the socket 20 from longitudinal movement through the fingers. The ratchet 22 is split to provide an opening to correspond with the slot 21 in the socket 20.

It will be observed particularly from Fig. 1 that the fingers 19 are of such a length 90 that their outer extremities terminate a short distance from lugs 23, which are upwardly extended from the head 18, according to the width of the slot 21 in the socket 20. The lugs 23 are disposed in the opposite edges of the head 18 and form continuations of the curvature of the fingers 19 to house the central portion of the socket 20 therebetween.

The head 18 is provided with a recess 24 105 in its outer end which is of circular formation for the reception of a stem 25 which is loosely inserted therein and which carries upon its outer end a pawl 26. The pawl 26 is formed of a portion of spring metal which 110 is secured adjacent one end upon the outer extremity of the stem 25 and having the

opposite end of the same directed upwardly and outwardly to engage with the teeth on the ratchet 22. The ratchet 22 is rigidly secured upon the socket 20 so as to move therewith and operates to admit of the rotation of the socket 20 in but one direction.

10 The opposite extremities of the socket 20 are externally threaded for the reception of the split rings 27 and 28 which form securing means for the ends of the wires which are inserted through the slot 21. The central portion of the socket 20 is considerably reduced to form shoulders 29 in the opposite ends of the same and to provide enlarged 15 chambers in the ends of the socket for the reception of the helices of the wire when being wound. The rings 27 and 28 which are split are formed of such a size that the extremities of the same are spaced at a distance equal to the width of the slot 21. It will thus be observed that when the socket 20 and the rings 27 and 28 are properly adjusted that the passages which are formed between the spaced extremities of the several 20 members of the implement are in registration with the slot 21 and admit of the insertion of a wire through the slot 21 and into the socket 20.

25 The outer extremity of the handle 10, which is pivotally mounted upon the pin 14 and adapted to swing independently of the head 18, is provided at its outer end with an eye 30 for the reception of a bail 31. The eye 30 is formed by the overturning of 30 the flattened extremity of the handle 10 and is engaged about one end of the bar 31 to hingedly support the same in position. The rear extremity of the handle 11 is curved outwardly to a slight degree for the purpose of forming a lip 32 to receive the free end of the bar 31 when the handles 10 and 11 are drawn together. By the provision of the bar, the handle 10 forms in conjunction with the handle 11, a suitable hand-grasp or lever 35 by which the implement may be operated, and also provides means whereby the handle 11 may be used independently of the handle 10, should a lever be desired, which does not necessitate the stretching of the fingers 40 to operate the same. It is readily observed that a section of the wire may be positioned in the slots 15 when the handles 10 and 11 have been diverged sufficiently to register the slots 15, and that when the handles 10 45 and 11 are drawn together, the wire is impinged between the cutting edges of the plates 12 and 13, and is thereby severed. The jaws 16 and 17 may be employed for rigidly securing one end of a wire during 50 the twisting process.

55 In the operation of the implement the members thereof are located within the fingers 19 to assume the position which is disclosed in Fig. 1, namely, that position in 60 which an uninterrupted passage is provided

to the central portion of the socket 20 from the side thereof and through the slot 21. A length of wire 33 is now positioned in the socket 20 through the slot 21 as is disclosed in Fig. 4, and a second length of wire 34 is 65 positioned in a like manner within the socket 20 and upon the upper face of the first wire 33. As the central portion of the socket 20 is considerably reduced the wires will be permitted of a limited movement therein. 70 The extremity of the length of wire 34 is now bent upwardly and outwardly through the slot 21 so as to project from the socket 20 between the fingers 19 and the adjacent split ring 27. The split ring 27 is now partially rotated by hand to dispose the split portion thereof out of alinement with the slot 21 in order to confine the wire 34 within the socket 20. The wire 33 is now held 75 rigidly in any suitable manner, as by pliers, 80 a vise or the like, when the head 18 is rotated to engage the pawl 26 with the ratchet 22, and to thereby rotate the socket 20. The rotation of the socket 20 carries the end of the wire 34 therewith and causes the securing 85 of the same about the wire 33. As the extremities of the socket 20 are enlarged the helices of the wire will be permitted to form within the end of the socket and are confined within such end so as to produce a uniform and neat winding. When a sufficient 90 number of windings is had with respect to the wire 34 the split ring 27 is rotated to register the split portion thereof with the slot 21 and the implement is moved longitudinally along the wire 33 from the wire 34. The implement is now disengaged from 95 the wire 33 and positioned on the wire 34, while the end of the wire 33 is bent in similar manner as the wire 34, and secured by 100 the opposite fingers 19 and the adjacent split ring 28. The same operation takes 105 place whereby the opposite ends of the wire is wound and a tight joint between the wires is secured. The plates 12 and 13 are now 110 engaged with the ends of the wire and rotated through the medium of the handles 10 and 11 to sever the ends of the wire and to further the neat appearance of the same.

Having thus described the invention what 115 is claimed as new is:—

1. A wire twisting implement including a head, a socket rotated in said head, fingers carried by said head for holding said socket in position, a ratchet formed centrally upon 120 said socket between said fingers, a pawl mounted in said head and engaged with said ratchet, split rings disposed in threaded relation upon the opposite ends of said socket, said socket having a longitudinal slot formed 125 in one side thereof for the reception of wires therethrough, and shoulders formed upon the inner wall of said socket adjacent the ends of the same.

2. A wire twisting implement including a 130

hollow socket, a head rotatably disposed about said socket, a ratchet carried by said socket, a pawl mounted in said head for engagement with said ratchet, fingers carried by said head and curved about said socket to retain the same in position, said socket having a longitudinal opening formed in one side thereof, and split rings engaged in threaded relation upon the opposite ends of 10 said socket.

3. The combination of a head, fingers carried by said head and bent circularly, a socket rotatably disposed between said fingers, a ratchet mounted rigidly on said socket and located between said fingers, and split rings adjustably disposed upon the opposite ends of said socket.

4. A wire twisting implement including a head, a handle carried by said head, a pair 20 of spaced fingers formed upon the outer end of said head and bent circularly, a cylindrical member disposed through said fingers, means disposed upon said cylindrical member and said head for imparting rotation

thereto, and wire retaining links adjustably disposed upon the opposite ends of said cylinder.

5. A wire twisting implement including a head, a socket mounted for rotation in the head and having ratchet teeth, said socket 30 also having a longitudinal slot in one side for the reception of a length of wire, a pawl loosely mounted in said head to seat against the teeth to admit of the rotation of the socket in one direction, locking rings carried 35 upon the ends of the socket to secure the wire therein for twisting the same, and a pair of handles carried by the head for swinging the head to effect the rotation of the socket.

In testimony whereof I affix my signature in presence of two witnesses.
